UNITED STATES PATENT OFFICE.

EZRA A. PECK, OF CHICAGO, ILLINOIS, ASSIGNOR TO THE DEERING HARVESTER COMPANY, OF SAME PLACE.

HARVESTER.

SPECIFICATION forming part of Letters Patent No. 567,196, dated September 8, 1896.

Application filed October 10, 1895. Serial No. 565,232. (No model.)

To all whom it may concern:

Be it known that I, EZRA A. PECK, of Chicago, county of Cook, and State of Illinois, have invented certain new and useful Im-
5 provements in Harvesters, of which the following is a full description, reference being had to the accompanying drawings, in which—

Figure 1 is a plan view. Fig. 2 is a side elevation of the harvester-frame, gearing, the forward portion of the wheel-frame, and the associated mechanism. Fig. 2^a is a side elevation of the rearward portion of the wheel-frame, the driver's platform, adjustment-levers, &c.; Fig. 3, a perspective view showing 15 the reel and its supporting devices; Fig. 4, a side elevation showing the parts directly concerned in moving the binder attachment fore and aft; Fig. 5, an enlarged plan view showing the main driving devices, and Figs. 20 6 and 7 details. Fig. 8 is a rear elevation of the axletree, harvester-frame, and portions of its suspension devices.

The object of my invention is to produce a wide-cut harvesting-machine that is more 25 simple in construction and better adapted to the reception of a binding attachment than has heretofore been found upon the market. The main frame, which is of T form, as will be seen in Fig. 1, consists mainly of the thrust-
30 tongue A and the axletree A', hinged thereto at the front end. The hinge is formed by yoke-pieces a and a', secured to the axletree, and by yoke-pieces a² and a³, secured to the thrust-tongue. Outreaching arms from these 35 yoke-pieces are adapted to receive a hinge-bolt a⁴. The axletree may consist of a pipe through which an axle may be passed, or to the ends of which stub-axles B and B' may be secured. The stub-axle B projects stub-
40 bleward from the axletree to receive the main wheel C and the sleeve A², and the stub-axle B' projects grainward from the opposite end of the axletree to receive the supporting-wheel C' in a similar manner. A brace A⁵, secured at a⁵ to the thrust-tongue and hinged at a⁶ in a yoke-piece a⁷, is secured near the grainward end of the axletree. The hinge a⁶ is substantially coincident with that of a⁴ and serves to brace the said axletree to the said 45 thrust-tongue. A bar A⁸, secured conveniently to the brace A⁵ at a⁸ and to the thrust-

tongue projecting therefrom in substantially a stubbleward direction, and a bar A⁹, secured to the said bar A⁸ and pivoted to the sleeve A², form, with the axletree and thrust-tongue, a gear-supporting frame. The thrust-tongue terminates at the rear end in a platform D, upon which the operator stands, and affords a bearing d for the forked tiller-shaft D'. The forked tiller-shaft rests upon the 55 axle of the steering-wheel D². To the tiller-shaft is secured a bracket d², which has secured to it the seat-spring and seat D³. It will thus be seen that the operator may, by swinging the tiller-shaft, guide the machine. 60

It will be understood that the foregoing constitutes the main supporting-frame of the machine and that the frame (hereinafter designated as the "harvester-frame") to which the parts directly concerned in cutting, conveying, elevating, and binding the grain are attached is supported upon outreaching arms E, E', and E¹⁰, secured to the axletree A'. The arm E is secured to the sleeve A², which may be considered as one part with the axletree because it is connected therewith by the bars of the gear-frame. The arm E' is secured to the yoke-piece a⁹ at the grainward end of the axletree, and the arm E¹⁰ to the yoke-piece a. A strut e' is secured to and 70 extends upwardly from the yoke-piece a⁹, and a strut e is secured to and extends upwardly from the sleeve A². Brace-rods e² and e³ connect the arms E and E' to the struts e and e', respectively. A rocking bracket E³, secured 75 to the thrust-tongue at a short distance behind the gear-frame, reaches upwardly therefrom and is connected with the struts e and e' by brace-rods e⁴ and e⁵. It is also connected to a strut e⁶, similar to those e and e', which 80 extends upwardly from the yoke-piece a and which is braced to the arm E¹⁰. The struts e, e', and e⁶ are braced in the direction of the length of the axletree by bars e⁸, e⁹, and e¹⁰. The bracket E³ is pivoted at its lower end 85 and connected to a hand-lever E⁴ by means of a brace-rod e⁷. The hand-lever E⁴ has a spring-latch mounted thereon adapted to engage a quadrant E⁵ and by means of which the harvester-frame may be adjusted to various heights from the ground in order to 90 cut a desired length of stubble. of the harvester-frame and the parts which it supports is counterbalanced by the springs F and F', connected to the bracket E⁴ by rods f and f' at their forward ends and to the 5 evener-yoke F² at their rearward ends. The evener-yoke is pivoted at about its center and is used so that any inequality in the strength of the spring can be compensated for. The harvester-frame G, which supports 10 the parts directly concerned in harvesting the grain, consists of bars g, g', g², and g³. The bar g has the guard-fingers secured thereto and is generally known as the "finger-bar." To the rear of the finger-bar and 15 extending along its length is the endless conveyer H, which is moved in a stubbleward direction to carry the cut grain to the elevators H', which need but a general description, being of the well-known form and consisting 20 of two endless aprons between which the grain is elevated to the binder-table. The binding attachment H² may be considered as being one of any of the well-known kinds and as having a frame h and frame-braces h'. 25 Said braces are shown as being hook-shaped at their inner ends to engage the binder-rail h².

h⁴ is a bracket having mounted thereon an antifriction-roller upon which the binder-frame is adapted to be moved fore and aft for the purpose of placing the band at about 30 the center of the length of the bundle.

The main wheel C has secured thereto a sprocket-wheel I, and at the rear of said wheel 35 is the counter-shaft I', suitably secured to supports i and i' upon the gear-frame. Upon the counter-shaft is rotatably mounted a sprocket-wheel I², around which and around the sprocket-wheel I is thrown a driving-chain 40 I³. The sprocket-wheel I² engages a clutch I⁴ upon the end of the bevel-gear J', which is mounted upon the support i. The clutch-moving mechanism is suitably connected to a foot-lever I⁵ adjacent to the seat of the 45 operator. A short diagonal shaft J is journaled in a bearing j upon the gear-frame, and has secured thereto a pinion J², meshing into the bevel-gear J' upon the counter-shaft. The bearing i' of the counter-shaft and the 50 bearing j of the diagonal shaft are preferably made as one piece and secured conveniently to the bar A⁵.

K is a shaft journaled in the harvester-frame in a convenient position under the elevator, from which shaft rotation is transmitted to the cutting, conveying, elevating, and binding devices. It is connected with the diagonal shaft J by a tumbling-shaft K' and universal joints k and k'. At the front 55 end of the shaft K is a crank L, connected to the sickle L' by a pitman L², so as to give the said sickle its required movement. A sprocket-wheel L³ upon the shaft K transmits rotation to the binder by a chain l' and 60 sprocket-wheel l², and a second sprocket-wheel l³ upon the immediate rear end of the said shaft K transmits the required movement 65

to the endless aprons of the conveyer and the elevator in the usual way.

M and M' are arms suitably secured and 70 braced to the harvester-frame and extend forwardly over the conveyer H. They are provided at their forward ends with bearings m and m'.

N and N' are levers pivoted by their studs 75 n and n' in the bearings m and m'. In the arms n² and n³ of said levers is journaled the reel-shaft O, carrying the reel-arms and fans O'. The arms n⁴ and n⁵ of the levers N and N' are connected by links P and P' to cranks 80 p and p' upon a rock-shaft P². The said arms n⁴ and n⁵ have several holes shown therein, by any of which they may be connected to the links P and P' for the usual purpose of adjustment of the various parts. 85

The rock-shaft P² is pivoted in brackets p² and p³ upon the arms M and M' at the rear of the platform conveyer. An arm P³ upon the rock-shaft is connected by a jointed link 90 P⁴ to a hand-lever P⁵, which lever is pivoted upon the thrust-tongue at a point adjacent to the seat of the operator. The link P⁴ is jointed at p⁴ and slides through the yoke p⁵, which yoke is close to the axis upon which the harvester-frame tilts, in order that when the 95 said frame is adjusted in height the position of the reel relative to the cutting apparatus will not be changed. A backboard R is hung upon the rock-shaft P² by arms r and r', and is connected to the link P⁴ by a rod 100 R². It is thus adapted to be rocked forward as the reel is rocked toward the cutter-bar, so as to form a shore or limit against which the head ends of the stream of grain are carried by the platform conveyer to the elevators. 105 The reel is given rotation from the main wheel by a sprocket-wheel Q', secured to the said wheel, and double sprocket-wheel Q², journaled upon the stud of the lever N, and sprocket-wheel Q³ on the reel-shaft, and by chains q 110 and q', thrown around said sprocket-wheel, as best shown in Fig. 2.

The binder-shifting mechanism consists of the hand-lever T, quadrant T', the rod t, connecting the said end lever with a lever t', pivoted upon the gear-frame, and a second rod t², connecting the said lever t' with the binder-frame at t³. The lever t' is for the purpose of allowing the rod t to be placed under the thrust-tongue or out of the way of the horses, 115 and is so situated that when the harvester-frame is adjusted vertically the binder attachment would not be moved out of adjustment because the rod t² would swing upon the lever t' as a center and with its length as a 120 radius describe with its forward end an arc that would be practically in a vertical line.

The bundle-carrier shown in the drawings is of the kind patented to John F. Steward, No. 482,931, dated September 20, 1892, and has 125 connected therewith an automatic dumping device.

What I claim as my invention, and desire to secure by Letters Patent, is—

1. In combination, a wheel-frame, a harvester-frame supported on outreaching arms of said wheel-frame and adapted to be rocked upon the axletree of said wheel-frame as an axis, a reel journaled upon said harvester-frame, and a jointed link guided adjacent to the axis of tilt, said jointed link connected to the reel-support and to a hand-lever under control of the operator, whereby the reel 5 can be adjusted and be held in a given position of adjustment relative to the harvester-frame when the said frame is rocked upon the axletree as an axis, to be itself adjusted vertically, and a swinging backboard 10 connected to said jointed link, substantially as described.

2. In a header a wheel-frame, a harvester-frame supported on outreaching arms therefrom and adapted to be rocked thereon, a 15 lever and suspension devices whereby the said harvester-frame can be rocked by the operator, springs counterbalancing the weight of said harvester-frame and an evener-yoke

to which the said springs are attached, substantially as described.

3. In combination, a wheel-frame, a harvester-frame supported upon outreaching arms of said wheel-frame, and adapted to be rocked upon the axletree of said wheel-frame as an axis, a reel journaled in bell-cranks 20 pivoted upon said harvester-frame, a rock-shaft journaled above the rear of said harvester-frame and connected by rods to said bell-cranks, a jointed link connected to said rock-shaft and to a hand-lever and guided at 25 a point adjacent to the axle, whereby the reel can be given different positions of adjustment relative to said harvester-frame and held in substantially such positions when the said harvester-frame is rocked upon said axletree, substantially as described.

EZRA A. PECK.
